UNITED STATES PATENT OFFICE.

GEORGE W. HOWES, OF DOWAGIAC, MICHIGAN, ASSIGNOR TO THE BECKWITH COMPANY, OF DOWAGIAC, MICHIGAN.

GRATE FOR FURNACES.

1,369,433.

Specification of Letters Patent. Patented Feb. 22, 1921.

Application filed January 30, 1919. Serial No. 274,055.

To all whom it may concern:

Be it known that I, GEORGE W. HOWES, a citizen of the United States, residing at Dowagiac, county of Cass, State of Michigan, have invented certain new and useful Improvements in Grates for Furnaces, of which the following is a specification.

This invention relates to improvements in grates for furnaces.

10 The main object of this invention is to provide an improved grate having rocking grate bars operatively connected by means of pinions in which the several grate bars may be quickly and easily placed in position in assembling or removed and replaced as occasion may require for repairs.

A further object is to provide a structure having these advantages which is simple and economical to produce and at the same 20 time strong and durable.

Further objects, and objects relating to structural details, will definitely appear from the detailed description to follow.

I accomplish the objects of my invention 25 by the devices and means described in the following specification. The invention is clearly defined and pointed out in the claim.

A structure which is a preferred embodiment of my invention is clearly illustrated 30 in the accompanying drawing, forming a part of this specification, in which:

Figure I is a detail view of a structure embodying the features of my invention, only such parts of a furnace being shown 35 as are deemed necessary to illustrate an application of my improvements.

Fig. II is a detail transverse section on a line corresponding to line 2—2 of Fig. I.

Fig. III is a front elevation of the front 40 bearing member and the retaining bar, the retaining bar being shown in its disengaged position.

In the drawing similar reference characters refer to similar parts throughout the 45 several views.

Referring to the drawing, 1 represents the ashpit body of a furnace. The grate bars 2 are shown conventionally and are provided with journals 3 at their rear ends and 4 50 at their front ends. One of the grate bars is extended at 5 to receive a shaking crank.

At the rear of the ashpit are bearings 6

with which the rear journals 3 of the grate bars may be engaged and disengaged by a longitudinal movement. The front ends of 55 the grate bars are supported by the bearing member 7 having bearings 8 therein with slots 9 extending from the bottom of the member and opening into the sides of these bearings 8. The edges 10 of these slots and 60 bearings are preferably scroll-shaped as illustrated, as this facilitates the engaging and disengaging of the journals with the bearings and the bringing of the pinions 11 into and out of mesh as the grate bars are 65 inserted or removed.

The journals of the grate bars are retained in their bearings by means of the retaining bar 12 which is pivoted at one end of the bearing member, as at 13, and detachably secured at the other end by means 70 of the pin 14 arranged through holes 15 in the bearing member and 16 in the retaining member.

The retaining bar when in its closed or 75 operative position extends across the slots 9 closing the same and thereby preventing the disengagement of the journals. This retaining bar is provided with upwardly projecting lugs 17 which engage the outer 80 sides of the journals limiting their lateral movement in the bearings, the lugs constituting, in effect, the side members of the bearings. The bearing member 7 is secured to the ashpit body 1 by means of bolts 18. 85

With this structure and arrangement of parts they may be economically produced and very conveniently assembled or disassembled as occasion may require.

In the accompanying drawing the various 90 parts are shown mainly in conventional form as the structural details of the ashpit body and the grate bars, other than the matter of their journals and the supports therefor, is not a matter of importance. 95

Having thus described my invention, what I claim as new and desire to secure by Letters Patent, is:

The combination with a body member, 100 grate bars having journals at their ends and provided with meshing pinions, rear bearings for the rear journals of the grate bars, a front bearing member supported by said body member in front of said pinions and

having a series of bearing openings there-
in with slots in its lower edge opening into
the sides of said bearing openings permit-
ting engagement and disengagement of the
5 journals therein and the meshing and dis-
engaging of the pinions by a lateral move-
ment in the same direction, and a retaining
bar mounted on said bearing member to

close said slots, said retaining bar being pro-
vided with upwardly projecting lugs con-
stituting bearing members for the outer
sides of said journals and whereby they are
retained in their bearings. 10

In witness whereof, I have hereunto set
my hand and seal.

GEORGE W. HOWES. [L. s.]
